Peter J. Beltz,
INVENTOR

BY Victor J. Evans

WITNESS:

Levi H. Evans

ATTORNEY.

UNITED STATES PATENT OFFICE.

PETER J. BELTZ, OF STILLWATER, MINNESOTA.

LATCH.

Application filed December 3, 1926. Serial No. 152,466.

This invention relates to latches, and one of its objects is to provide a simple, durable, inexpensive and efficient latch for gates, doors and the like, which can be attached thereto in an expeditious manner, and when arranged in operative position will positively prevent the opening of the gate, door etc. until the latch is actuated for that purpose.

A further object of the invention is to provide a latch that is semi-automatic in its operation and will latch itself upon the closing of the closure having the latch associated therewith.

Another object of the invention is to provide a latch that can be opened by the application of a finger thereto, and upon the opening thereof it will force and swing the closure to which it is associated to open position.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an edge elevation of the latch forming the subject matter of the present invention and showing the same attached and in latched position.

Figure 2 is a sectional view taken on line 2-2 of Figure 1.

Figure 3 is a similar sectional view but showing the position of the latch member for receiving the keeper incident to the latter moving the same to operative position.

Figure 4 is a sectional view taken vertically through the keeper and showing the same in applied position.

Figure 5 is a detail view of the latch member per se.

Referring to the drawings in detail the letter A indicates a post or a frame for a gate or door B and secured to the gate or door as shown in Figure 4 is a substantially U-shaped attaching member 1 which has centrally projecting from its bight portion a keeper formed by a headed pin 2 and a sleeve 3.

Secured to the frame of the gate is an attaching member 4 as best shown in Figures

2 and 3, and fulcrumed to the attaching member adjacent one side thereof is a latch member 5 having an arm 6 extending from its fulcrumed point and terminating in a finger piece 7 bent at right angles thereto, and extending in an opposite direction from the fulcrumed point is a lever 7' having a cam surface 8 which terminates at its inner end in a recess 9 which as best shown in Figure 3 is arranged at a right angle to the cam surface 8 and extends into the latching arm 10 which is also provided with a cam surface 11 and terminates in its outer end in a finger piece 12.

The attaching member 4 has portions cut therefrom and arranged at right angles thereto to provide stops 13 and 14. The stop 13 limits the movement of the latch member in one direction and is arranged in the path 75 of the lever 7', while the stop 14 limits the movement of the latch member in its opposite direction and is arranged in the path of the latching arm 10.

From the above description and disclosure 80 of the drawings, it will be obvious that the latch which forms the subject matter of the present invention is semi-automatic in its operation and when associated with a closure structure such as a gate, door or the like, 85 upon closing of the closure member the keeper will engage the cam surface 11 of the latch arm 10 and slide along said cam

surface until it engages the lever 7' which forces the keeper into the recess 9, and when 90 the keeper is in this last mentioned position, the closure member cannot be moved to open position until force is applied to the arm 6 or the latching arm 10, and this force will cause the keeper to be moved out of the 95 recess for engagement with the cam surface 8 of the lever 7' and it will be obvious that if

the arms 6 or 10 are actuated in a quick manner, the force applied to the latch member will cause the closure member to be 100 swung to open position. The latch member can be actuated with very little effort on the part of the operator to swing the closure member to open position, and when it is desired to close the closure member a slight 105 push thereon will be all that is necessary to cause the latch member to operate and receive the keeper in its recess to retain the closure member in closed position.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A latch of the character described comprising a fulcrumed latch member, an arm included in said latch member, a latch arm formed with said latch member and being provided with a cam surface, a lever formed with said latch member and being oppositely disposed with respect to the arm first mentioned, said lever being provided with a cam surface terminating at its inner end into a recess disposed at right angles to the cam surface, a keeper adapted for cooperative engagement with the cam surfaces and recess respectively, and stops for limiting the movement of said latch member in opposite directions.
2. A latch of the character described com-

prising an attaching member, a latch member fulcrumed to said attaching member, an arm formed with said latch member and extending from its fulcrumed point, a finger piece formed with said arm, a lever provided with a cam surface and being oppositely disposed with respect to said arm, a latch arm having a curved surface, stops arranged on said attaching member and in the path of the lever and latching arm respectively to limit the movement of the latch member in opposite directions, and a keeper arranged for cooperative association with the cam surface of the latch arm whereby the latter will position the same in a recess disposed at right angles to the cam surface of the lever, and the cam surface of said lever being adapted for slidable engagement with the keeper for operating the latter as and for the purpose specified.

PETER J. BELTZ.
